UNITED STATES PATENT OFFICE.

EDWARD C. AHLHEIM, OF MANSFIELD, OHIO.

FLUSH-VALVE.

1,187,595.

Specification of Letters Patent. Patented June 20, 1916.

Application filed May 17, 1915. Serial No. 28,547.

To all whom it may concern:

Be it known that I, EDWARD C. AHLHEIM, a citizen of the United States of America, residing at Mansfield, in the county of Rich-
5 land and State of Ohio, have invented cer-
tain new and useful Improvements in
Flush-Valves, of which the following is a
specification.

This invention relates to certain new and
10 useful improvements in flush valves and has
for its primary aim to provide a valve
which is automatic and efficient in operation
and simple of construction.

A further object resides in the compact
15 arrangement of parts wherein adjustment
of interval of flow of the flushing liquid
may readily be obtained.

The invention further resides in the
20 salient features of construction, arrange-
ments and combinations of parts described
in detail in the following specification, suc-
cinctly defined in the appended claims and
illustrated in the accompanying drawings,
wherein—

25 Figure 1 is a top plan view of the invention
in its preferred embodiment; Fig. 2 is a
vertical section on the line 2—2 of Fig. 1;
Fig. 3 is a horizontal section on the line
3—3 of Fig. 2; Fig. 4 is a vertical section
30 on the line 4—4 of Fig. 1, the view being at
right angles to the section of Fig. 2 and hav-
ing the lower section or chamber removed;
and Fig. 5 is a horizontal section on the line
5—5 of Fig. 2 showing the lower section.

35 The valve comprises, in its illustrated
form, a casing consisting of an upper sec-
tion A and a lower section B, the latter
having an annular flange 1 seating in an
annular seat 2 of the upper section and se-
40 cured thereto by screws 3, suitable packing
4 being interposed therebetween.

In upper section A is a laterally directed
inlet 5 leading to an inner valve chamber 6
in which operates a vertically moving valve
45 7 for engaging on seat 8 to close the opening
9 in the top wall of the valve chamber
6. Opening or outlet port 9 establishes
communication between the valve chamber
6 and an encircling space or chamber 10
50 which is shown as being interrupted by
webs 11 and 12 supporting the inner valve
chamber 6 from the surrounding wall of
the casing. The substantially annular
chamber 10 of the upper section coincides
55 with the chamber 10 of the lower section.

and the webs 11 and 12 are likewise con-
tinued, said continuations of the webs sup-
porting a piston chamber 13 of smaller
diameter than chamber 6 and arranged in
coincidence therewith. A vertical conduit 60
14 in web 12 establishes communication be-
tween the bottom of chamber 13 and the
upper portion of chamber 6, said conduit or
passage 14 terminating in ports 15 and 16
leading to the respective chambers. Valve 65
7 normally closes inlet 5 and port 16 and is
formed with a hollow stem 17 which is pro-
vided with openings 18 adapted, when the
stem is opened, to provide for the escape of
the fluid from chamber 6 to chamber 10. 70
Slidable in the valve stem is a push rod 19
carrying on its upper and outer end a push
button 20 and on its lower terminal a valve
21 normally engaging on seat 22 to close
the passage provided in the hollow valve 75
stem. This valve 21 is retained seated by
the pressure of the fluid in chamber 6, the
latter being in constant communication with
the main by passage 23 leading from the
inlet 5 to a point below the valve 7. 80

Screwed into the lower end of upper sec-
tion A is an interposed wall 24 dividing
chambers 6 and 13 and provided with a cen-
tral opening 25 through which slides a stem
or pin 26 capped by valve 27 which seats 85
on the upper face of wall 24 to minimize
the leakage between the chambers. An
abutment or trip member 28 has its stem 29
threaded in the lower end of stem 26 for
vertical adjustment within the chamber 13. 90
Slidable in the latter is a vertically mov-
able piston 30 which has a tubular stem 31
slidable through a boss 32 of a bottom clo-
sure 33 for the chamber 13. The tubular
stem provides a drainage for any liquid 95
which may have leaked into the chamber
above the piston.

In operation, assuming that the parts are
in their normal position as shown in Fig. 2,
the button 20 is initially pushed down-
wardly to unseat valve 21 whereupon the
pressure in the chamber 6 will be relieved,
the liquid passing from passage 23 and the
chamber 6 up through stem 17 and out
openings 18 into the encircling chamber 10 105
from whence the fluid makes its escape
through the outlet 34. Further depression
of button 20 engages the latter with the
stem 17 and forces the latter with its sup-
ported valve 7 to the bottom of chamber 6, 110

opening inlet 5 and ports 9 and 16, whereupon the water will pass freely through the chamber 10, a portion also being conducted through conduit 14 into chamber 13 below the piston 30. This exerts an upward pressure on the latter, causing the same to rise to engage the trip plate 28 and slide it vertically. Upward movement of stem 26 will cause the head or valve 27 to engage with and effect a seating of the valve 21 on seat 22. Fluid, thus continuing to enter through passage 23, will elevate valve 7 to close inlet 5 and stop the flow of fluid. The fluid below piston 30 will gradually escape through a suitable opening 35 provided in closure 33 and the affected parts gravitate to normal position.

What is claimed is:

1. A valve of the character described comprising a casing consisting of a lower section and a superposed upper section, an inner valve chamber in the upper section supported from the casing in spaced relation thereto by a web to form a surrounding chamber, an inlet communicating with the valve chamber, the latter having an outlet in its top wall communicating with the surrounding chamber and a passageway connecting the inlet with the bottom portion of the valve chamber, a valve operable in the valve chamber to normally close the inlet and opening in the top wall of the chamber and having a hollow stem slidably supported by the casing, said valve stem being formed with an opening establishing communication between the surrounding chamber and stem, a rod slidable in the valve stem, a valve on the rod normally closing communication between the valve stem and valve chamber, a piston chamber arranged in the lower casing section in coincidence with the valve chamber and supported from the casing by a web constituting a continuation of the first web to form a surrounding chamber coinciding with the surrounding chamber of the upper section, a dividing wall interposed between the valve chamber and piston chamber, a valve seating stem slidably supported in the dividing wall and projecting into the chambers on each side, said stem being adapted to engage with the rod supported valve to seat the latter, a piston operable in the piston chamber by fluid pressure beneath the piston to slide the valve seating stem, the web and its continuation being formed with a conduit establishing communication between the valve chamber and piston chamber at a point in the latter below the piston and being normally closed by the first mentioned valve, and an outlet for the casing.

2. A flush valve comprising a casing having an inlet and an outlet, a valve chamber interposed therein between the inlet and out-

let, a valve arranged within the chamber to close normally communication between the inlet and outlet and provided with a passage adapted to establish communication between the valve chamber and outlet, communicative means between the inlet and the valve chamber at a point below the valve, a second valve for closing the passage in the first valve, means for opening the valves, means normally free of and adapted to engage the second valve to close the latter and thereby confine the fluid under pressure beneath the first valve for closing the latter, and means under control of the first valve for actuating the second valve closing means. 70 75 80

3. A flush valve comprising a casing having an inlet and an outlet, a valve chamber interposed therein between the inlet and outlet, a valve arranged within the chamber to close normally communication between the inlet and outlet and provided with a passage adapted to establish communication between the valve chamber and outlet, communicative means between the inlet and the valve chamber at a point below the valve, 85 a second valve for closing the passage in the first valve, means for opening the valves, a valve closing member movable into the valve chamber to engage with the second valve for closing the latter, and fluid operated 90 means normally under control of the first valve for actuating the valve closing member. 95

4. A flush valve comprising a casing having an inlet and an outlet, a valve chamber interposed therein between the inlet and outlet, a valve arranged within the chamber to close normally communication between the inlet and outlet and provided with a passage adapted to establish communication between the valve chamber and outlet, communicative means between the inlet and the valve chamber at a point below the valve, a second valve for closing the passage in the first valve, means for opening the valves, a valve closing member slidably mounted in the casing and adapted for engagement with the second valve to close the latter, fluid operated means for actuating the slideable valve closing member, and a fluid passage provided for conducting fluid from the valve chamber to the fluid operated means, said fluid passage being normally closed by said first valve. 100 105 110 115

5. A flush valve comprising a casing having an inlet and an outlet, a valve chamber interposed therein between the inlet and outlet, a valve arranged within the chamber to close normally communication between the inlet and outlet and provided with a passage adapted to establish communication between the valve chamber and outlet, communicative means between the inlet and the valve chamber at a point below the valve, a second valve for closing the passage in the 120 125 130

- first valve, means for opening the valves, a valve closing member slidably mounted in the casing and adapted for engagement with the second valve to close the latter, a piston 5 slidable in the casing for actuating the slide-
able valve closing member, and a fluid passage provided in the casing for conducting fluid from the valve chamber for action against the piston.
- 10 6. A flush valve comprising a casing having a valve chamber and a piston chamber arranged in coincidence therewith, a dividing wall partitioning the valve chamber from the piston chamber, an inlet and an outlet provided for the valve chamber, a communicative passage between the afore-
said chambers, a valve arranged in the valve chamber to normally close the communicative passage and communication between the 15 inlet and outlet, said valve being provided with a passage for establishing communication between the outlet and valve chamber, a second valve for closing the passage in the valve under fluid pressure, a conduit lead-
ing from the inlet to the valve chamber at a point below the first valve, means for opening the valves, a valve closing member slidably mounted in the dividing wall for closing the second valve, and a fluid oper-
ated piston arranged in the piston chamber 20 for actuating the valve closing member.
7. A flush valve comprising a casing having an inlet and an outlet, a valve chamber interposed therein between the inlet and outlet and communicating therewith, a valve in the chamber normally closing communication between the inlet and outlet, said valve including a hollow stem provided with an opening establishing communication be-
tween the valve chamber and outlet, a valve normally closing the hollow stem, a communicative passage leading from the inlet to a point in the chamber below the valve, 25 means to operate the second valve to open the valve stem, a piston chamber, a piston operable therein, and means operable by the piston to seat the second valve.
8. A flush valve comprising a casing having an inlet and an outlet, a valve chamber 30 interposed therein between the inlet and outlet and communicating therewith, a valve in the chamber normally closing communication between the inlet and outlet, said valve including a hollow stem provided with an opening establishing communication be-
tween the valve chamber and outlet, a valve normally closing the hollow stem, a communicative passage leading from the inlet to a point in the chamber below the valve, 35 means to operate the second valve to open the valve stem, a piston chamber, a piston operable therein, and means operable by the piston to seat the second valve.
9. A flush valve comprising a casing having an inlet and an outlet, a valve chamber 40 interposed therein between the inlet and outlet and communicating therewith, a valve in the chamber normally closing communication between the inlet and outlet, said valve including a hollow stem provided with an opening establishing communication be-
tween the valve chamber and outlet, a valve normally closing the hollow stem, a communicative passage leading from the inlet to a point in the chamber below the valve, 45 means to operate the second valve to open the valve stem, a piston chamber arranged in coincidence with the valve chamber, a dividing wall between the chambers, a stem slid-
able in the dividing wall for engage-
ment with the second valve to seat the latter, and a fluid operable piston in the piston chamber for sliding the valve seating stem.

In testimony whereof I affix my signature 85
in presence of two witnesses.
